Primary Examiner — T. Chase Nelson*Assistant Examiner* — Mark Cavanna(74) *Attorney, Agent, or Firm* — Shumaker, Loop & Kendrick LLP(57) **CLAIM**

The ornamental design for a galley appliance, as shown and described.

DESCRIPTION

FIG. 1 is a front and right side perspective view of a galley appliance showing our new design;

FIG. 2 is a front elevational view thereof;

FIG. 3 is a top plan view thereof;

FIG. 4 is a bottom plan view thereof;

FIG. 5 is a right side elevational view thereof; and,

FIG. 6 is a left side elevational view thereof.

The broken lines shown in the drawing disclosure are for illustrative purposes only and form no part of the claimed design.
